(57) **CLAIM**

The ornamental design for an automobile side strake or replica thereof, as shown and described.

DESCRIPTION

FIG. 1 is a left elevation view of an embodiment of an automobile side strake or replica thereof in accordance with the present design;

FIG. 2 is a front, left perspective view thereof;

FIG. 3 is a rear, left perspective view thereof;

FIG. 4 is a top plan view thereof;

FIG. 5 is a front elevation view thereof;

FIG. 6 is a right elevation view thereof; and,

FIG. 7 is a rear elevation view thereof.

The dot-dash lines define the boundary of the claimed design and form no part thereof. The portions shown in dashed broken lines depicts portions of the automobile side strake or replica thereof that form no part of the claimed design.

1 Claim, 7 Drawing Sheets
